Primary Examiner — Jennifer L Rempfer*Assistant Examiner* — Bethany Louise Mallino*(74) Attorney, Agent, or Firm* — John M. Lipchitz(57) **CLAIM**

The ornamental design for a stand for a shaving razor, as shown and described.

DESCRIPTION

FIG. 1 is a front perspective view of a razor stand showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown illustrate portions of the razor stand and form no part of the claimed design.
